UNITED STATES PATENT OFFICE.

EVA MARGARETHA SCHEFFBUCH, OF RIDGEWOOD HEIGHTS, NEW YORK.

DESIGN FOR A PUZZLE BOX OR CASE.

SPECIFICATION forming part of Design No. 30,159, dated February 7, 1899.

Application filed January 11, 1899. Serial No. 701,881. Term of patent 31 years.

To all whom it may concern:

Be it known that I, EVA MARGARETHA SCHEFFBUCH, a citizen of the United States, residing at Ridgewood Heights, in the county of Queens and State of New York, have invented and produced a new and original Design for Puzzle Boxes or Cases, of which the following is a specification, reference being had to the accompanying drawings, forming part thereof, in which—

Figure 1 is a plan view of a puzzle box or casing showing my new design, and Fig. 2 a diagonal section thereof on the line 2 2.

As shown in the drawings, the leading or material features of my newly-designed puzzle box or case consist of the bottom 5, which is rectangular in form and provided with upright side and end walls 6, each corner being provided with a segmental upright wall 7, which walls form triangular corner chambers 8, and said segmental walls 7 being provided in the bottom thereof with open spaces 9, and the center of the box or casing being open

and the upper or top surface of the bottom 5 being plane and smooth throughout its extent. The upper surface of the bottom is also provided parallel with each of the side and end walls with an ornamental border 10 and centrally of each border with inwardly-directed supplemental ornamental figures 11, 30 said borders and figures serving to give the entire design a fanciful and ornate appearance.

Having fully described my invention, I claim as new and desire to secure by Letters 35 Patent—

The design for a puzzle box or case herein shown and described.

In testimony that I claim the foregoing as my invention I have signed my name, in presence of the subscribing witnesses, this 9th day of January, 1899.

EVA MARGARETHA SCHEFFBUCH.
